5 Claims. (Cl. 316—1)

This invention relates to the manufacture of cathode-ray tubes, and particularly to the manufacture of such tubes which are adapted for high-voltage operation, e.g., operation with interelectrode voltages in excess of 10 kilovolts. The invention is particularly useful in manufacturing television picture tubes, and will be described for convenience in that connection.

A conventional television picture tube comprises a multiple electrode electron gun supported on a press which is sealed into the neck of the envelope after formation of the luminescent screen. The electron gun assembly includes a thermionic cathode, one or more anodes, and an intervening control grid for determining the instantaneous intensity of the electron beam originating at the thermionic cathode. The final anode of the electron gun is conventionally operated at voltages substantially in excess of 10 kilovolts; final anode voltages from 20 to 25 kilovolts are customary in present-day television picture tubes. If the tube is of the electrostatically focused variety, the gun assembly also comprises the electrostatic focusing system, and it is also quite conventional to include a getter ring as a part of the gun assembly.

Because of the high electrode voltages employed and the close interelectrode spacings, one of the difficulties encountered in subsequent operation has been that of intermittent arcing within the electron gun. In some instances, and especially when an arc is induced between the emissive surface of the thermionic cathode and one of the other electrodes, such arcing may lead to loss of emission from the cathode with an accompanying adverse effect on the life of the tube. Moreover, arcing in the gun structure may in some instances result in damage to the external circuit elements to which the gun electrodes are connected, as is well known in the art.

Television picture tubes have also been observed, in many instances, to produce an undesired faint glow on the phosphor screen, with an adverse effect on picture contrast, and this effect is usually attributed to cold emission, of which the major portion is generally conceded to originate from the gun electrodes or other elements constituting the gun assembly.

Both intermittent arcing and cold emission are generally attributed to the presence of lint, dust, phosphor particles, grease, or other extraneous matter on or in the gun assembly, and many precautions have been taken to assure utmost cleanliness for this reason. Measures previously taken include special rinsing baths for the gun subassemblies and the provision of hygienically clean assembly areas. However, such measures are expensive and cumbersome to employ, and arcing and cold emission have remained a major production problem.

Another measure which has been employed to reduce arcing and cold emission in finished tubes has been the so-called "spot knocking" procedure. In this procedure, the gun electrodes are all connected together and a high voltage, of the order of 40 to 50 kilovolts, is impressed between the final anode and the interconnected gun electrodes. While this voltage is applied, the neck of the envelope is tapped in an effort to loosen dust, lint or other foreign particles or extraneous matter which may be present in the gun structure. Some of the extraneous particles are burned out and others shaken loose by this

procedure. It is of course an unwieldy procedure, and while some temporary reduction in the tendency toward arcing or cold emission may be observed in some instances, the "spot knocking" technique fails to eliminate the cause of the trouble because extraneous particles or their combustion products remain within the envelope and constitute a source of possible future difficulty.

It is the principal object of the present invention to provide a new and improved method of minimizing arcing in the electrode system of an electron-discharge device of the type adapted for high-voltage operation.

It is a further object of the invention to provide such a new and improved method which is convenient and inexpensive to employ in the large-scale commercial production of such devices.

In accordance with the invention as applied to the manufacture of a cathode-ray tube comprising an electrode system mounted in an evacuated envelope and adapted for high-voltage operation, the new and improved method of minimizing arcing during subsequent operation of the electrode system comprises the completing of all manufacturing and assembling operations on the electrode system which can be performed outside of the envelope, thereafter completely immersing the electrode system, initially at a predetermined ambient temperature, in a liquid medium maintained at a temperature substantially below this ambient temperature and having a boiling point intermediate the temperature of the liquid medium and the ambient temperature, to induce localized turbulence in the liquid medium at the areas of contact thereof with the electrode system, withdrawing the electrode system from the liquid medium when the turbulence has at least substantially abated and thereafter, before said electrode system reaches said ambient temperature, and without further processing of the electrode system, sealing the electrode system into the envelope.

The features of the present invention which are believed to be novel are set forth with particularity in the appended claims. The organization and manner of operation of the invention, together with further objects and advantages thereof, may best be understood by reference to the following description taken in connection with the accompanying drawing, in which the single figure is a side view, partly in cross-section, showing the electron gun assembly of a television picture tube being immersed in a liquified gas in accordance with the present invention.

In accordance with the present invention, as applied to the manufacture of television picture tubes, the electron gun assembly 10 is constructed in an entirely conventional manner, including its assembly to a glass press 11 which is provided with an exhaust tubulation or stem 12. After all of the manufacturing and assembly operations which can be performed outside the envelope have been completed, the gun assembly, in the condition shown in the figure, is temporarily immersed in a liquid medium 13 maintained by means of a vacuum flask 14 or the like at a temperature substantially below the ambient temperature of the gun assembly immediately prior to immersion. Liquid medium 13, which is preferably a liquefied gas such as liquid air, liquid nitrogen or liquid oxygen, has a boiling point intermediate the temperature of the liquid medium and the initial ambient temperature of the gun assembly prior to immersion. In practice, the initial ambient temperature of the gun assembly is not critical, and no pre-heating or pre-cooling is required; immersion of the gun assembly at substantially room temperature as determined by the ambient factory conditions is preferred for convenience.

Upon immersion of the gun assembly in liquid medium 13, as shown in the figure, a localized turbulence is observed in liquid medium 13 at the areas of contact thereof

with the electrode system 10. If the immersion operation is performed manually, by grasping stem 12 and suspending the electrode system in liquid medium 13, the vibrations induced by the turbulence are quite perceptible to the touch. The attendant ebullition or boiling action is readily observed visually. The turbulence is induced by localized boiling of the liquid medium 13, which takes place without the application of heat other than that introduced by immersion of the gun assembly at or near room temperature, since the boiling point or ebullition temperature of the liquid is well below room temperature. The turbulence, with attendant vibration of the electrode system, is observed until the temperature of the gun structure 10 has dropped below the boiling point of liquid 13, at which time the turbulence subsides and the gun structure 10 may be withdrawn. The entire operation may be performed manually or automatically, and requires only from 5 to 10 seconds.

As soon as possible after withdrawing the gun assembly from the vacuum flask 14, and without any further processing of the electrode system, the gun assembly 10 is inserted in the neck of the picture tube envelope and press 11 is sealed in place in an entirely conventional manner. The tube is then processed to completion in the usual way.

Liquid air, liquid nitrogen and liquid oxygen are preferred because of their chemical compatibility with the other components of the picture tube, and because immersion in such media does not result in the formation of foreign deposits on the gun parts. The ambient temperatures of these media at atmospheric pressure are approximately equal to their ebullition temperatures and are about -125 degrees centigrade for liquid oxygen, -150 degrees centigrade for liquid air, and -200 degrees centigrade for liquid nitrogen, the latter being preferred as providing the most pronounced ebullition or boiling action.

It has been discovered that the use of this simple additional procedure in the commercial production of television picture tubes effects a substantial reduction in the amount of arcing and cold emission encountered in the finished tube in subsequent operation. While accurate measurement is difficult to achieve, it may be demonstrated that the threshold of arcing voltage is increased in this manner by at least 4 and in some instances as much as 10 kilovolts or more, thus effectively eliminating arcing as a cause of in-plant rejects, and eliminating the necessity for employing the "spot knocking" procedure. This improvement is apparently attributable to the highly effective cleaning action provided by localized ebullition or boiling of the liquefied gas which imparts a substantial high-frequency vibration to the electrode system 10. This vibration literally shakes particles of dust, lint or other contaminants off the gun structure and is possibly assisted by quick-freezing of these contaminants which may render them brittle and more easily separable from the electrode surfaces. The particles thus removed from the electrode system are readily observable as a precipitate in the liquid medium 13, even with gun assemblies with which the utmost care in maintaining cleanliness has been exercised in prior processing and handling.

It is important to seal the electrode system into the envelope as soon as possible after withdrawing the gun assembly from liquid medium 13, and in any event without performing any intervening processing steps; re-exposure of the gun assembly to air for as much as several minutes before sealing and after withdrawal from medium 13 may permit a further accumulation of foreign particles on the surfaces of the gun assembly, as may be demonstrated by redipping in medium 13 and observing the additional precipitate which is formed.

It has also been observed that, although the gun assembly as immersed in the refrigerated liquid medium 13 includes a cathode sleeve which has been pre-coated as an intermediate step in the process of forming a therm-

ionic surface, the turbulence of liquid medium 13 and the attendant vibration of the gun parts is not sufficient to substantially disturb the coated cathode surface.

There is nothing critical about the immersion process of the present invention, and it can be performed by an entirely unskilled operator without the provision of expensive manufacturing equipment or production space. The benefits of the invention are achieved with immersion for only 5 or 10 seconds, although immersion for a longer time is not harmful. Production experience has shown that it is extremely difficult with conventional processing to maintain an incidence of arcing in production tubes as low as 10 percent; by employing the procedure of the present invention, the incidence of arcing is reduced to a fraction of one percent. At the same time, a reduction in cold emission by as much as 25 to 50 percent is achieved.

While a particular embodiment of the invention has been shown and described, it will be obvious to those skilled in the art that changes and modifications may be made without departing from the invention in its broader aspects, and, therefore, the aim in the appended claims is to cover all such changes and modifications as fall within the true spirit and scope of the invention.

We claim:

1. In the manufacture of a cathode-ray tube comprising an electrode system mounted in an evacuated envelope and adapted for high-voltage operation, the method of minimizing arcing in said electrode system in subsequent operation which comprises:

completing all manufacturing and assembling operations on said electrode system which can be performed outside said envelope;

thereafter completely immersing said electrode system, initially at a predetermined ambient temperature, in a liquid medium maintained at a temperature substantially below said ambient temperature and having a boiling point intermediate said temperature of said liquid medium and said ambient temperature to induce localized turbulence in said liquid medium at the areas of contact thereof with said electrode system;

removing said electrode system from said liquid medium when said turbulence has at least substantially abated;

and thereafter, before said electrode system reaches said ambient temperature and without further processing of said electrode system, sealing said electrode system into said envelope.

2. In the manufacture of a cathode-ray tube comprising an electron gun having a thermionically emissive cathode mounted in an evacuated envelope and adapted for high-voltage operation, the method of minimizing arcing in said electrode system in subsequent operation which comprises:

providing an electron gun assembly, including a cathode element having a coated surface adapted to be rendered thermionically emissive in subsequent processing of said tube, on which all manufacturing and assembling operations which can be performed outside said envelope have been completed;

thereafter completely immersing said electron gun assembly, initially at substantially normal room temperature, in a liquefied gas having a boiling point substantially below said room temperature, whereupon substantial turbulence of said gas is induced at the areas of contact thereof with said electron gun assembly;

removing said electron gun assembly from said liquefied gas when said turbulence has at least substantially abated;

and thereafter, before said electron gun assembly reaches said room temperature and without further processing thereof, sealing said electron gun assembly into said envelope.

5

3. The method of claim 2, in which said liquified gas is one of the group consisting of liquid air, liquid nitrogen and liquid oxygen.

4. The method of minimizing arcing in a cathode-ray tube which comprises subjecting the electron gun of said cathode-ray tube to ebullition in a liquified gas at a temperature substantially below normal room temperature, and sealing said electron gun into the cathode-ray tube envelope before said electron gun has reached room temperature.

6

5. The method of claim 4, in which said liquified gas is one of the group consisting of liquid nitrogen, liquid air, and liquid oxygen.
